UNITED STATES PATENT OFFICE.

DUDLEY G. STONE, OF NEGAUNEE, MICHIGAN.

STOPPER FOR OIL-CANS OR LAMP-FILLERS.

SPECIFICATION forming part of Letters Patent No. 439,984, dated November 4, 1890.

Application filed March 11, 1890. Serial No. 343,480. (No model.)

To all whom it may concern:

Be it known that I, DUDLEY G. STONE, of Negaunee, in the county of Marquette and State of Michigan, have invented a new and 5 useful Improvement in Stoppers for Oil-Cans or Lamp-Fillers, of which the following is a full, clear, and exact description.

My invention relates to an improvement in oil-cans or lamp-filers of any description, 10 and has for its object to provide a device of simple and durable construction and capable of convenient manipulation, which will be kept in place as a stopper by means of its own weight, and not be liable to displacement by 15 any jarring or tipping movement of the can.

The invention consists in the novel construction and combination of the several parts, as will be hereinafter fully set forth, and pointed out in the claim.

20 Reference is to be had to the accompanying drawings, forming a part of this specification, in which similar letters and figures of reference indicate corresponding parts in all the views.

25 Figure 1 is a side elevation of a portion of a can and its spout, illustrating the application of the stopper thereto. Fig. 2 is a section through the spout and a portion of the stopper, and Fig. 3 is a perspective view of 30 the stopper detached.

The stopper is constructed of two parts or sections—namely, a cap or hood 10 and a shank or stem 11. The cap or hood may be made of wood, metal, cork, rubber, or equivalent material and shaped in the ordinary manner, if 35 desired. The inner walls of the cap are, however, preferably made to practically correspond to the exterior contour of the upper end of the can spout or nozzle 12, to which the 40 stopper is to be applied, as is best illustrated in Fig. 2.

The shank or stem 11 consists of a piece of metal of any convenient length and of a size and shape to admit of its being easily inserted 45 into the spout or nozzle of the can. The cap

or hood is secured to the upper end of the shank or stem in any convenient manner. Ordinarily the connection is effected by passing the end of the rod through the top of the cap and then turning or riveting the projecting 50 extremity of the rod sufficiently to form a head 13. The cap may be held in position and prevented from sliding upon the shank by reducing the upper end of the rod comprising the shank and carrying the said reduced 55 end through the cap, as shown at *a* in Fig. 2. Thus when the head 13 is formed, the top of the cap is firmly clamped between the said head and a shoulder *a'* upon the shank.

The completed stopper may be attached to 60 the can 14 by a chain or in any other approved way, or it may be left unattached, as shown in the drawings.

One great advantage in this style of stopper outside of its cheapness and easy application is that its weight tends to keep it in place, and thus the cap is kept drawn down closely over the nozzle, and the stopper is not likely to be disturbed by reason of any jar or tipping movement of the can. 70

Having thus described my invention, I claim as new and desire to secure by Letters Patent—

As an improved article of manufacture, a stopper for the nozzles of oil-cans or similar 75 vessels, consisting of a cap or hood and a metal bar forming a stem or shank, one end of which bar is secured to the center of the head of the cap, the other end being made to project beyond the bottom of the latter and adapted to 80 enter freely the spout or nozzle of a can, whereby the stopper will be held to the spout or nozzle by its weight and all liability of its being accidentally displaced avoided, substantially as shown and described.

DUDLEY G. STONE.
